(57) **CLAIM**

The ornamental design for a cutting and embossing machine, as shown and described.

DESCRIPTION

FIG. 1 is a front elevational view of a cutting and embossing machine showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a third perspective view thereof;

FIG. 10 is a fourth perspective view thereof;

FIG. 11 is a front elevational view of the cutting and embossing machine in a use state;

FIG. 12 is a rear elevational view thereof;

FIG. 13 is a left side view thereof;

FIG. 14 is a right side view thereof;

FIG. 15 is a top plan view thereof;

FIG. 16 is a bottom plan view thereof;

FIG. 17 is a first perspective view thereof;

FIG. 18 is a second perspective view thereof;

FIG. 19 is a third perspective view thereof; and,

FIG. 20 is a fourth perspective view thereof.

The broken lines in the figures depict portions of the article which form no part of the claimed design.

1 Claim, 20 Drawing Sheets
